UNITED STATES PATENT OFFICE.

HOWARD R. LARSEN, OF MILWAUKEE, WISCONSIN.

TOY.

1,425,869.

Specification of Letters Patent. Patented Aug. 15, 1922.

Application filed May 3, 1921. Serial No. 466,381.

To all whom it may concern:

Be it known that I, HOWARD R. LARSEN, a citizen of the United States, and resident of Milwaukee, in the county of Milwaukee 5 and State of Wisconsin, have invented certain new and useful Improvements in Toys; and I do hereby declare that the following is a full, clear, and exact description thereof.

The invention relates to improvements in 10 toys generally and more particularly to a type of the same adapted for the amusement of small children.

The principal object of the invention is to provide for a toy of the character specified, and one, in its preferred embodiment, having the form of a fanciful figured novelty, and of a nature involving extremely simplified features of construction, arrangement and manipulation whereby to be exceedingly inexpensive to manufacture.

Another object of the invention is to provide for a toy of the type mentioned, and one wherein the figured portion of the same is arranged to have a reciprocatory movement imparted thereto through the medium of a simple actuating means, whereby to greatly add to the amusement features to be obtained in the mere viewing of its comical or fanciful configuration.

With the foregoing and other objects in view, the invention resides in the certain novel and useful construction and arrangement as will be hereinafter more fully described, as set forth in the appended claims, 30 and illustrated in the accompanying drawing, in which:—

Figure 1 is a side elevation, partly in section, of the preferred form and configuration of the toy, and

Figure 2 is a horizontal section taken on the line 2—2 of Figure 1.

Referring to the drawing, the numeral 10 indicates a body portion or member, preferably formed of a suitable length of tubular wooden or metal stock open at both of its ends, and constituting the handle of the toy. Movable vertically of the body or handle 10 is a rod 11 upon the upper end of which is secured a supporting plate 12 having an intermediate portion normally resting in flat contacting relation on the upper end of the body or handle. The plate 12 is preferably of sheet metal and is provided with a forwardly and downwardly curved portion 13 and a rearwardly and upwardly inclined or angularly disposed portion 14,

which portions are shaped to characterize the breast and collar portions, respectively, of a fanciful costume, such as is usually worn by circus clowns. Mounted on and suitably secured to the intermediate portion of the plate 12 is a head portion 15 which may be of any desired configuration, such as characterizes a clown's head, and rising from the upper portion of the head portion 15 is a body portion 16 having the form of a clown's usual head-gear or cap. The face of the head portion 15 is disposed in a plane immediately above the center of the portion 13, of the plate 12, while the rear portion 14 of the latter, extends upwardly in rear of the head portion after the usual manner of the collar portion of a clown's costume. The portions 13 and 14, of the supporting plate 12, the head portion 15, and the head-gear 70 or cap body are to be suitably colored or painted in conformity with the usual colors used in the make-up of a clown, or to otherwise characterize any of the well known figures of mythical or historical origin.

For imparting a vertical reciprocatory movement to the rod 11, a flexible actuating medium 17, such as a suitable length of cord or the like, is provided, and the same is trained over a supporting element or pin 18 extending transversely of the upper end portion of the body or handle 10 to one side of the center of the bore of the tube to give clearance for the free movement of the rod past the same, one end of the flexible medium 17 being secured, as at 19, to the lower end of the rod 11, and the other end thereof depending free of the lower open end of the body or handle 10 and carrying a finger piece or ring 20 at its extremity.

In the manipulation of the toy thus provided, the rod 11, with the attached character portions, is to be projected upwardly of the body or handle 10, by the pulling of the free depending end of the flexible medium or cord 17 in a downward direction with one hand, while the body or handle is firmly gripped in the other hand, and by varying the degree of the pulling force, the rod 11 may be successively reciprocated within the body or handle 10, or the same may be projected entirely from the upper end thereof.

It is well understood that, while the toy has been specifically described and illustrated, various modifications of the same, 110 or changes in the detailed construction, arrangement, size and configuration of the

parts thereof may be resorted to without departing from the spirit of the invention or from the scope of the appended claims.

Having thus fully described the invention, 5 what is claimed is:

1. A toy comprising a tubular handle portion, a rod movable in the handle portion, a head portion having a fanciful configuration carried at one end of said rod, and means 10 for imparting a reciprocatory movement to said rod.

2. A toy comprising a tubular handle portion, a rod movable within the handle portion, a head portion having a fanciful configuration carried at one end of said rod, and means 15 extending within said handle portion for imparting a reciprocatory movement to said rod.

3. A toy comprising a tubular handle portion, a rod, a head portion having a fanciful configuration carried at one end of said rod and supporting the same within said 20 handle portion and means extending within the said handle portion for projecting said rod outwardly of one end thereof.

4. A toy comprising a tubular handle portion, a rod, a head portion having a fanci- 25

ful configuration carried at one end of said rod and supporting the same inwardly of one end of said handle portion, and a flexible medium extending inwardly of the opposite end of said handle portion and arranged to be manipulated for the reciprocation of said rod.

5. A toy comprising a tubular handle portion, a rod, a head portion having a fanciful configuration carried at one end of said rod and supporting the same inwardly of the upper end of said handle portion, a pin extending transversely of the upper end of said handle portion to one side of said rod, and a flexible cord extending inwardly of the lower end of said handle portion and having one end trained over said pin and connecting the lower end of said rod, the other end of said flexible cord depending free from the lower end of said handle portion and adapted to be manipulated in a manner to project said rod upwardly of the latter.

In testimony that I claim the foregoing I 50
have hereunto set my hand at Milwaukee, in
the county of Milwaukee and State of Wisconsin.

HOWARD R. LARSEN.
